UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed May 21, 1919, Serial No. 298,589. Renewed July 30, 1925.

To all whom it may concern:

Be it known that I, ALFRED B. FOWLER, a citizen of the United States, residing at Beverly, in the county of Essex and State 5 of Massachusetts, have invented certain new and useful Improvements in Sewing Machines; and I do hereby declare the following to be a full, clear, and exact description of the invention, such as will enable others 10 skilled in the art to which it appertains to make and use the same.

This invention relates to sewing machines, and more particularly to curved hook needle 15 sewing machines employed for sewing together the soles and uppers of shoes.

The present embodiment of the invention is designed especially to sew together the soles and uppers of turned shoes although, with slight changes, it may be employed for 20 sewing the inseams of welted shoes.

The primary object of the invention is to improve the construction and mode of operation of certain parts and devices of this class of shoe sewing machines.

The features of the invention consist in the 25 constructions, combinations and arrangements of parts hereinafter described and claimed, the advantages of which will be obvious to those skilled in the art.

The several features of the invention will be understood from the following description and accompanying drawings, in which Fig. 1 is a front elevation of the head of a shoe sewing machine embodying the features of the present invention in their preferred form; Fig. 2 is an enlarged front elevation, partly in section, of a portion of the head of the machine illustrated in Fig. 1; Figs. 3 and 4 are detailed sectional views of a thread cutting and holding device of the machine, which sections are taken on the lines 3—3 and 4—4, respectively, of Fig. 2; Fig. 5 is a side elevation looking from the right, partly in section and with a portion of the casing removed; Fig. 6 is a sectional elevation looking from the right and taken on a plane just to the right of the needle segment; Fig. 7 is a side elevation looking from the left with a portion of the casing removed; Fig. 8 is a plan view partly in section of a portion of the head of the machine; Figs. 9 to 12, inclusive, are diagrammatic views showing in plan the successive positions which the needle, thread finger,

and looper assume in the performance of 55 their cycle of operations, a portion of the sole and upper of a shoe being shown in section through the plane of the seam; Fig. 13 is a side elevation corresponding to Fig. 12 and showing the shoe in vertical section; Fig. 14 is a vertical sectional view taken axially through the main or cam shaft of the machine and showing the driving and stopping mechanism in stopping position; Fig. 15 is a sectional view taken on the line 15—15 of Fig. 14 with a portion of the casing broken away; Fig. 16 is a view similar to Fig. 15 but with the parts shown in the 60 positions which they assume during the normal operation of the machine; Fig. 17 is a plan view, partly in section, of the driving and stopping mechanism in stopping position; Fig. 18 is a view similar to Fig. 17 but with the low speed driving mechanism thrown into operation; Fig. 19 is a rear 70 elevation, partly in section and with a portion of the casing removed, of the driving and stopping mechanism; and Fig. 20 is a sectional view taken on the line 20—20 of Fig. 19. 75

The mechanism illustrated in the drawings is provided with a curved hook needle, a needle guide, a thread arm, a looper, a main take-up, an auxiliary take-up, a back gage, a back rest or bunter and a tension wheel, 80 all of which parts have the same general arrangement and mode of operation, except as hereinafter described, as the corresponding parts of the machine illustrated and described in applicant's pending application, 85 Serial No. 254,104, filed Sept. 14, 1918.

The needle 2 is secured in the usual manner to a needle segment 4 which is pivotally mounted on a hollow shaft 6 and connected by a link 8 to a cam actuated lever 10. The needle guide 12 is secured to one end of a shaft 14 that extends axially through the hollow shaft 6. An arm 16 is secured to the other end of the shaft 14 and its free end has a pin and slot connection with the forward end of a lever 18, the other end of which lever is provided with a roll that engages a cam groove 20 in an oscillating lever 22 which is connected by a link 24 to the cam actuated lever 10. 100

In the illustrated machine, the thread finger 26 (Figs. 2, 5, 6 and 8) moves in the direction of the line of feed outside of the

line of the seam in an arc of a circle having a vertical axis or an axis perpendicular to a plane which is tangent to the path of the needle at the sewing point. The thread finger is secured to the lower end of a vertical shaft 28, on the upper end of which shaft is secured a gear 30 that meshes with rack teeth 32 formed on the forward end of a horizontally sliding bar 34. The bar 34 is actuated to impart the desired movement to the thread finger 26 by means of a roll on the rear end of the bar which engages a cam groove 36 in the oscillating lever 22.

The looper 38 (Figs. 2, 7 and 8) is secured 15 to the inner end of a lever 40. The lever 40 is actuated to move the looper in one direction by means of a slide 42 and is actuated to move the looper in a transverse direction by means of a slide 44. The lever 40 is connected to the slide 42 through an arm 46 secured to a pivoted stud 48 and having its free end pivotally connected to the outer end of the lever 40. To the pivoted stud 48 is secured a gear segment 50, the teeth of 25 which are operatively engaged by rack teeth 51 formed on the slide 42. The slide 44 is connected to the lever 40 by means of a pin 52 secured to the forward end of the slide and extending through an elongated slot in 30 the lever. The slide 42 is operatively connected to a cam actuated lever 54 by means of an adjustable link 56, and the slide 44 is operatively connected to a cam actuated lever 58 by means of an adjustable link 60.

35 The combined action of the devices for actuating the looper causes the looper to completely encircle the needle in such manner as to result in the formation of a chain stitch, the loop of which is twisted through a complete turn. In encircling the needle, the looper first passes the thread across the plane of the needle outside of the circle of the needle, then across the plane of the needle inside of the circle of the needle, and finally again across the plane of the needle outside of the circle of the needle. The thread is caused to completely encircle the needle before entering the hook so that when the needle retracts, a twist is formed in the 40 needle loop. The actuation of the thread finger in the direction of the line of feed and in a horizontal plane ensures such threading of the needle in a uniformly reliable manner. In Figs. 9 to 12 inclusive, are illustrated different relative positions assumed by the needle, looper and thread finger during the formation of a stitch. In Fig. 9 these parts are shown just after the looper has made its first movement across the plane of the needle and outside of the circle of the needle. In Fig. 10 the thread is shown completely encircling the needle. In Fig. 11 the parts are shown just before the needle pulls the loop through the previously formed loop. Fig. 12 shows the needle at the limit 45

of its loop drawing stroke, and also in this figure is indicated by a broken line the path traversed by the looper during a cycle of operations.

The travel of both the thread finger and 70 looper in a horizontal plane or in a plane tangent to the path of the needle at the sewing point gives a maximum amount of clearance at all times between these parts and the sole of the shoe.

75 The main take-up of the illustrated machine comprises a thread truck 62 (Fig. 6) mounted on a lever 64 pivoted at 66 on the frame of the machine. The lever 64 is actuated to move the thread truck in an arc 80 by means of a link 68 having one end pivoted on the lever 64 and its other end pivoted on a cam actuated lever 70. From the thread truck 62 the thread passes over a thread truck 72 which is mounted on a fixed shaft 85 or rod 74. The truck 72 forms a part of an auxiliary take-up and this take-up also comprises a lever 76 pivoted on the rod 74. From the thread truck 72 the thread passes over a thread truck 80 mounted on the forward end of the lever 76 and thence through the looper. The lever 76 is acted upon by a spring 82, one end of which is secured to the lever 76 and the other end to a screw 84. The spring 82 tends to raise the lever 76 95 until a projection 86 thereon engages the lower end of an adjustable abutment screw 88. The tension of the spring 82 may be adjusted, if desired, by adjusting the screw 84.

100 The thread handling devices of the machine are so arranged and operated that the main take-up acts to exert a stitch setting strain on the seam and draw off thread for the next loop from the tension wheel 90, 105 hereinafter described, when the needle is in its forward position and extending through the work. The main take-up then falls during the thread measuring movement of the thread arm, during the looping movement of the looper, and during the retracting movement of the needle. As the needle reaches the limit of its retracting movement, it exerts a pull on the thread to tighten the preceding loop, such pull tending to move 110 the auxiliary take-up lever 76 away from the abutment screw 88 and placing the auxiliary tension spring 82 under tension. To render the action of the main take-up, the auxiliary take-up and the needle reliable and uniform under all conditions of sewing, means are provided in the machine illustrated in the drawings which insure that the pull exerted upon the thread by the needle as it reaches the limit of its backward movement, shall always be against the resistance offered by the spring 82 of the auxiliary take-up and not against the resistance offered by the tension wheel 90. To this end, the main take-up lever 64 is provided with an 115 120 125 130

extension 92 having a cam surface 94 which cooperates with a roll 96 on the auxiliary take-up lever 76 to maintain the thread truck 80 of the auxiliary take-up in a raised position during the latter portion of the taking-up stroke of the main take-up and during the first portion of the down stroke of the main take-up. This permits the auxiliary take-up to yield to the required extent, when the needle exerts a pull on the thread at the end of its retracting movement, without bringing up against a positive stop.

In the illustrated machine the work is fed by means of a channel guide 91 (Figs. 1, 2, 5 and 8) which is provided with ratchet-like teeth for effective engagement with the work. A rectilinear movement is imparted to the channel guide which is similar to the movement imparted to the channel guide of the machine disclosed in applicant's pending application hereinbefore referred to. The channel guide is secured to an arm 93 depending from a feed slide 95 mounted on the rod 74. The feed slide is adapted to be laterally reciprocated on the rod to advance and retract the channel guide and is adapted to be rocked on the rod to swing the channel guide transversely of the direction of feed toward and from the work. The means for reciprocating the feed slide 95 comprises a lever 100 (Fig. 8) pivoted at 102 on a stud secured to the frame of the machine. The forward end of the lever is suitably connected with the feed slide by an adjustable block and slot connection and its outer end is provided with a cam roll which engages a cam 104 on the main shaft of the machine. The rocking movement of the feed slide is accomplished by a lever 106, (Fig. 5) one end of which is forked to engage a squared portion of the feed slide and the other end of which is provided with a stud or a cam roll 108 which engages a cam on the main shaft. The lever 106 is held from lateral displacement by means of a headed stud 110 that extends through a transverse slot in the lever;

To provide for an adjustment of the channel guide transversely of the direction of feed, the lever 106 is made adjustable. To this end, the lever is made in two parts, both of which are fulcrumed on a pin 112 so that by swinging the parts of the lever on the pin 112, the position of the channel guide may be varied. The parts of the lever are held in the desired adjusted position by means of a bolt 114 which extends through a slot 116 in one of the parts and through an aperture in the other part.

The illustrated machine is provided with a channel closing device 118 (Fig. 6) that acts to close the channel during the later part of the forward movement of the needle and is raised out of engagement with the

work when the needle acts to draw the loop through the channel, so that the closing of the channel does not interfere with the feeding of the work or with the proper drawing of the loop through the work. The mechanism for actuating the channel closing device is extremely simple in construction and efficient in operation. This device is formed on the forward end of a lever 120 secured to a stud 122 pivotally mounted in the frame of the machine. The lever is swung to bring the channel closing device into engagement with the work by means of a torsion spring 124 and is brought out of engagement with the work by means of a roll 126 mounted on the rear end of the lever which engages a cam surface 128 formed on the under side of the link 8 through which the needle segment is actuated. The work engaging movement of the channel closing device is limited by the engagement of a lug 130 on the forward arm of the lever 120 with an adjustable abutment screw 132 secured to the frame of the machine.

The machine is provided with a back rest or bunter, which comprises a roll 134 (Figs. 5 and 6) mounted on a forwardly spring pressed slide 136. The machine is further provided with a back gage 138 which is connected as hereinafter described to a locking slide 140. The slides 136 and 140 and the means for locking them together may be and preferably is the same as disclosed in said pending application. The back gage is formed on the forward end of a back gage carrier 142 which is connected by a link 144 with the back gage locking slide 140, one end of the link being pivoted upon a stud 146 secured to the carrier 142 and its other end being pivoted on a stud secured to the slide 140. The back gage carrier is guided by means of a pin 150 secured to the frame of the machine which extends through a horizontal slot in the carrier. The free end of an arm 152 is also pivoted upon the stud 146 which arm is secured to a rock shaft 154. An arm 156 is pivoted upon the shaft 154 and is connected to the arm 152 by a torsion spring 158 which is normally under no tension. During the work piercing movement of the needle 2, the back gage is caused to lightly engage the work and is then pressed against the work under increasing pressure by means of a stud 160 on the needle actuating link 8 which engages the arm 156 and through the torsion spring 158 and arm 152 thus actuates the back gage. The back gage and back rest are locked in engagement with the work at the limit of this stroke of the needle and until the needle returns to the limit of its loop drawing stroke. In order that the back gage may not interfere with the feeding of the work, means are provided for retracting the back gage after the needle

has reached the limit of its loop drawing movement. To this end, the rock shaft 154 carries an arm 162, the free end of which is engaged by a lug 164 projecting from a sleeve 166 that is mounted to slide on a vertical rod 168. A spring 170 is coiled about the rod 168 and is interposed between the lower end of the sleeve 166 and a collar 172 secured to the rod. When the back 10 gage is unlocked at the limit of the loop drawing stroke of the needle, the spring 170 acts through the connecting mechanism to retract the back gage. As the torsion spring 158 is under no tension at this time 15 it will not interfere with this action of this coiled spring and, also, as the strength of the coiled spring is considerably less than that of the torsion spring 158, the coiled spring will not interfere with the action 20 of the torsion spring in advancing the back gage during the work piercing stroke of the needle. It will be apparent that the upward movement of the rod 168 upon stopping the machine increases the tension 25 of the coiled spring 170, which insures the complete retraction of the back gage at this time.

The tension wheel 90 (Figs. 2, 6 and 7) hereinbefore referred to, over which the 30 thread is passed in the usual manner, is secured to a short shaft 174 journaled in the machine frame. In order to provide the proper tension on the thread, the rotation of the shaft 174 carrying the tension wheel 35 is opposed by a brake comprising a brake drum 176 secured to the shaft and over which passes a brake strap 178. The brake strap has one end secured to a stud 180 on the frame of the machine and its other end secured to a stud 182 on the free end of an 40 arm 184 pivoted at 186 on the frame. The arm 184 is urged downwardly to maintain the strap 178 under tension by means of a spring 188 interposed between the top surface of the arm 184 and the lower end of a screw 190. The tension of the spring may be varied to vary the tension of the brake 45 strap by adjusting the screw 190.

At a predetermined point in the final 50 cycle of operations of the stitch forming devices before the machine is stopped, the tension of the brake strap 178 is released to permit thread cutting and holding devices, hereinafter described, to draw the end of the thread a considerable distance from the 55 stitch forming devices so that the thread cutting and holding devices will not interfere with the removal of the shoe. To this end, at a predetermined point in the final 60 cycle of operations, the rod 168, hereinbefore referred to in connection with the description of the operation of the back gage, is moved upwardly and by engagement with the free end of the tension arm 184 swings 65 the arm against the action of its spring 188

to release the tension of the brake strap 178. After the machine is started and during the formation of the first stitch, the tension of the brake strap is maintained released in order to permit the thread to be freely 70 drawn over the tension wheel by the thread handling devices. This is accomplished by means of a latch 192 which is snapped into engagement with the free end of the arm 184 when the arm is swung upwardly by the 75 treadle rod 168 as above described. The latch 192 is pivoted at 194 on the frame of the machine and is provided with a lug 196 adapted to engage the under side of the free end of the arm 184. The latch is swung 80 towards the arm 184 by a coiled spring 198, the ends of which are fast to studs on the latch and arm. Near the completion of the formation of the first stitch, the latch is released and disengaged from the arm 184, to 85 permit the arm to apply the brake, by the engagement of a roll 200 on the lever with a cam surface 202 on the oscillating lever 22 hereinbefore referred to.

Referring particularly to Figs. 1 to 4, inclusive, the illustrated machine is provided with devices for cutting and holding the thread at the completion of the sewing. These devices are timed to operate so as to 90 cut off the thread during the last cycle of 95 operation of the stitch forming devices and to hold the end of the thread leading to the supply until the machine is again set into operation. The machine is also provided with a stop mechanism which in cooperation 100 with the thread cutting devices stops the machine with the needle in retracted position free from the thread.

The devices for cutting and holding the thread comprise jaws 204 and 206 which are 105 carried by a lever 208 pivoted at 210 on the frame of the machine, the jaw 204 being formed on the end of said lever and the jaw 206 being formed on the lower end of a lever 212 that is pivotally mounted on the 110 lever 208. A spring 213 having one end secured to the upper end of the lever 212 and its other end secured to a pin 214 projecting from the lever 208 tends to close the jaws. The mounting of the lever 212 on the lever 115 208 comprises a cap screw 215 which extends through apertures in said levers and is provided with a nut 216 on its end. The sides of the jaws are pressed together by means of a spring 217 coiled about the shank 120 of the screw 215 and interposed between a side of the lever 212 and the head of the screw. The jaws are provided with thread gripping surfaces 220 that are transversely inclined upwardly and outwardly and the 125 jaw 206 is provided with a shearing edge 222 formed thereon. A plate 224 is secured to the inner side of the jaw 204 by means of a pin 209 and the screw 215 which extends through an aperture in the plate. This plate 130

is provided with a shearing edge 226 that is arranged to cooperate with the shearing edge 222 on the jaw 206. During the normal operation of the machine, the lever 208 is positioned to hold the jaws stationary at a considerable distance to the right of the plane of the needle. While the machine is being stopped, the lever is swung over to a position where the jaws can cut and grip the thread and is then moved back toward normal position with the end of the thread leading to the supply held by said jaws. The mechanism for actuating the lever 208 comprises a link 228 which connects the lever to the free end of an arm 230 secured to a rock shaft 232.

By actuating the rock shaft 232, the thread cutting and holding jaws may be moved toward and from the work. In order to vary the extent of this movement of the jaws, the link 228 is adjustably connected to the arm 230 by means of a bolt 234 upon which the link is pivoted, which bolt extends through an elongated slot in the arm 230 and is adapted to be adjusted longitudinally of the slot. The rock shaft 232 is actuated in a direction to move the jaws toward the needle by means of a spring 236 having one end secured to the frame of the machine and its other end secured to the free end of an arm 238 secured to the rear end of the rock shaft. The actuation of the rock shaft is controlled by a cam lever 240 having one end pivoted at 242 on the machine frame and having its other end provided with a stud 244 which engages a slot in the free end of an arm 246 secured to the rock shaft. The lever 240 is provided with a roll 248 which engages a cam 250 loosely mounted on the rock shaft.

During the normal operation of the machine, the jaws are held in retracted position by the engagement of a high part 252 of the cam with the roll 248. At a predetermined point in the final cycle of operation of the stitch forming devices, the cam 250 is rotated in a clock-wise direction and as a low part 254 of the cam approaches the cam roll, the jaws are moved toward the plane of the needle. During this movement of the jaws, a cam surface 258 on the upper end of the lever 212 engages a cooperating surface 260 on a latch 262 which swings the lever 212 in a direction to open the jaws as shown in Fig. 2, at which time the jaws are positioned between the looper and the needle with the thread between them. The latch 262 is pivoted at 263 and is urged in a clock-wise direction against a stop 264 by means of a torsion spring 265 having one end connected to the upper arm of the latch and its other end connected to the frame of the machine. The upper end of the lever 212 is then carried past the end of the latch 262 which permits the spring 213 to swing the lever 212 in a direction to close the jaws whereby the thread is cut and the end thereof leading to the supply is gripped by the jaws. The timing of this operation is such that the thread is cut just before the needle acts to draw the last formed loop through the work. As the high part 266 of the cam engages the cam roll 248, the thread gripping jaws are thereby retracted, with the end of the thread held between them, to the position indicated in Fig. 1. The thread is permitted to be drawn freely through the looper by the jaws, at this time, as the brake on the tension wheel has been released as previously described. When the jaws have been thus moved to the limit of their retracted position, the stopping devices hereinafter described act to stop the machine, at which time the cam roll 248 is engaged by a point on the high part 266 of the cam.

When the machine is again started, the thread gripping jaws are at once advanced to give up thread to the thread finger so that in this machine the thread finger assists in the formation of the first stitch. The thread is held by the thread gripping jaws during the formation of the first stitch and during a part of the second work piercing stroke of the needle. When the machine is started, the cam 250 is again rotated and this advancing movement of the jaws is effected by means of a concentric low part 267 of the cam. This part of the cam extends substantially half way around the cam so that the gripping jaws are thereby held in stationary position. When a depression 268 of the cam is brought into engagement with the cam roll, the jaws are still further advanced until the cam surface 258 on the lever 212 engages the latch 262 whereupon the jaws are opened to release the thread and then are immediately brought back to normal position by the engagement of the high part 252 of the cam with the cam roll.

The described rotation of the cam 250 is controlled by the rod 168 which, when it is moved upwardly, in addition to releasing the brake connected with the tension wheel as previously described, also throws in a one revolution clutch mounted on the shaft 232 which through suitable gearing connecting it with the main shaft, drives the cam at one half the speed of the main shaft. This rod 168 is operatively connected to the clutch through a three arm lever 270 pivoted at 272 on the frame of the machine and connected through an adjustable link 274 with a bell crank lever 276. The bell crank lever 276 is provided with members which, when the rod 168 is raised, are disengaged from members of the clutch which permits the clutch to be thrown in. The driving connection between the clutch and the main shaft, the clutch, and the members formed on the bell crank lever 276 which control the operation of the clutch, may be and preferably are

the same as the corresponding parts illustrated and described in applicant's pending application hereinbefore referred to, to which reference is hereby made for a detailed description of these parts.

The driving and stopping mechanism of the present embodiment of the invention includes a high speed driving mechanism and a low speed driving mechanism. The high speed driving mechanism is adapted to drive the machine during the normal operation thereof, and the low speed driving mechanism is adapted to be thrown in when the high speed driving mechanism is thrown out, and is designed to act first to reduce the speed of the machine and then to drive the machine at a low speed to stopping position.

Referring to Figs. 1 and 14 to 20, inclusive, the high speed driving mechanism comprises a continuously driven pulley 280 loosely mounted on the main shaft 282 of the machine, which pulley is adapted to be clutched to the shaft by the engagement of a friction clutch face 284 on the interior thereof with a conical friction clutch face 286 on a clutch member 288 which is splined on the shaft.

The low speed driving mechanism comprises a spiral gear or worm wheel 290 which is journaled on a collar 292 secured to the shaft. The worm wheel 290 is adapted to be clutched to the shaft by the engagement of a conical friction clutch face 294 on a clutch member 296 secured to the worm wheel, with a friction clutch face 298 formed on the interior of the clutch member 288. The spiral gear 290 is continuously driven, through speed reducing gearing, from the high speed pulley 280. This gearing comprises a spiral gear or worm 300, secured to the forward end of a counter shaft 302, which operatively engages the gear 290. On the rear end of said counter shaft is secured a spiral gear 304 which engages a spiral gear 306 carried by a counter shaft 308. A spur gear 310 is secured to the right end of the counter shaft 308 and is operatively engaged by a spur gear 312 secured by screws 314 to the pulley 280.

The clutch member 288 is urged towards the low speed clutch member 296 by means of springs 316 (Fig. 14) located in sockets in the member 288 and interposed between the ends of the sockets and a collar 318 formed on the main shaft. The clutch member 288 is adapted to be shifted toward the pulley 280 by means of a collar 320 which is splined on the hub of the collar 292. The collar 320 actuates the clutch member 288 through sliding pins 322 which extend through apertures in the collar 292. The collar 320 is provided with an annular groove 324 which is engaged by studs or rolls on a forked arm 326 secured to a rock shaft 328. An arm 330 (Fig. 1) is secured

to the forward end of the rock shaft and the free end of this arm is connected by a rod 332 with a treadle mechanism (not shown) located at the base of the machine. When the rod 332 is depressed by means of the treadle mechanism, the arm 330 is swung downwardly which, through the rock shaft 328 and arm 326 shifts the collar 320 to bring the clutch member 288 into clutching engagement with the high speed pulley 280, whereupon the machine is driven at high speed. When the treadle rod 332 is released, a torsion spring 334 having one end connected to a lug on the arm 326 and its other end connected to the frame of the machine, acts to shift the collar 320 to the left, whereupon the springs 316 are permitted to shift the clutch member 288 to throw out the high speed driving mechanism and immediately to throw in the low speed driving mechanism. This movement of the collar 320 toward the left is limited by the engagement of a stop lug 336, secured to the arm 330, with the lower end of a latch lever 338. At a predetermined point in the rotation of the main shaft, a cam 340 carried by the clutch member 288 engages the upper end of the latch lever 338, whereupon, the lever is swung out of engagement with the lug 336 which permits the torsion spring 334 to shift the collar 320 into position so that its further rotation will cause a lug 342 formed thereon to engage a lug 344 on a controlling cam block 346. The cam block 346 is normally stationary and is loosely mounted on the main shaft. The engagement of the lug 342 with the lug 344 results in the cam block being carried in unison with the main shaft for a predetermined part of one revolution, whereupon the collar 320 is shifted to move the lug 342 out of engagement with the cam block. The cam block is held in this advanced position by the engagement of a lug 348 thereon with the upper end of a spring actuated latch lever 350 pivoted at 352 on the frame of the machine.

The movement of the collar 320 out of engagement with the cam block is accomplished by means of a plunger 354 mounted to slide in a bearing in the frame of the machine which engages a block 356 adjustably secured to the upper end of the forward fork of the collar shifting arm 326. The plunger is actuated by the engagement of a roll 358 on the left end of the plunger with a cam 360 carried by a hand wheel 362 secured to the end of the main shaft of the machine.

The foregoing described advancing movement of the cam block 346, through suitable connections, acts to raise the rod 168 and thereby release the brake connected with the tension wheel and to throw in the clutch which operates the thread cutting and holding devices.

The connections between the cam block 130

and the rod 168 comprise a roll 365 which engages a cam groove in the cam block, which roll is mounted on the upper end of a lever 366 pivoted at 367 on the frame of the machine, and having its lower end connected by an adjustable link 368 with an arm 369 of a bell crank lever. The bell crank lever is pivoted at 370 on the frame of the machine and its other arm 372 is pivoted to the lower end of the rod 168.

At the completion of a predetermined number of degrees of rotation of the main shaft after the collar 320 is shifted out of engagement with the cam block, the collar 15 is further shifted to the right a sufficient distance to disconnect the low speed driving mechanism and to bring the clutch member 288 into neutral position whereby the machine is stopped. This additional movement 20 of the collar 320 is accomplished by means of a plunger 374 mounted to slide in a bearing in the cam block, which plunger engages the upper end 376 of the rear fork of the collar shifting arm 326. This plunger 25 is actuated by the engagement of a roll 378 mounted on the left end thereof with a cam 380 carried by the hand wheel 362. After the collar 320 is thus shifted by the plunger 374 to bring the clutch member 288 into neutral position, the collar 320 is held in this 30 position, until the driving mechanism is again thrown into operation by the operator, by a spring pressed latch 381 pivotally mounted on the cam block 346, which latch 35 moves into a position to engage the adjustable block 356 as indicated in Fig. 17. When the machine is at rest, therefore, the main shaft is free from any driving or braking mechanism and can be rotated by hand by means of the hand wheel 362 as may be desired.

It will be noted that when the treadle rod 332 is allowed to rise in stopping the machine the clutch mechanism is actuated to shift directly from the high speed to the low speed drive and that this shift from the high to the low speed drive may occur at any point in the revolution of the main shaft. It will also be noted that this shift 45 from the high to the low speed drive does not immediately bring the controlling cam block 346 into operation but that the operation of the cam block is delayed until the main shaft has been driven by the low speed 50 mechanisms for at least a predetermined interval. This result is accomplished by the provision of the latch 338 and the cam 340 by which it is actuated at a predetermined point in the rotation of the main shaft. The 55 latch 338 can only be actuated when the low speed drive is in operation and the engagement of the lug 342 on the clutch shifting collar 320 with the lug 344 on the cam block 346 occurs a certain and definite number of 60 degrees of revolution after the latch 338 has

been operated. This insures a sufficient period of time between the throwing in of the low speed drive and the actuation of the controlling cam block to slow down the speed of the shaft to that of the low speed 70 drive and thus the thread cutting and other mechanisms which are controlled by the cam are actuated while the machine is running at comparatively slow speed. The action of these mechanisms and particularly the 75 action of the thread cutting and holding mechanisms is thus rendered certain and reliable regardless of the speed at which the machine is run during its normal operation 80 in sewing a seam.

When the treadle rod 332 is depressed by the treadle mechanism to start the machine, a lug 382 projecting from the lower end of the arm 326 engages an abutment screw 384 secured to the lever 350, thereby swinging the lever on its pivot to disengage the upper end thereof from the lug 348 on the cam block 346. This allows a torsion spring 386 having one end secured to the frame of the machine and its other end secured to the cam block to return the cam block to its initial position. This retracting movement of the cam block, which is in a direction reverse to that of the rotation of the main shaft, is limited by the engagement of a lug 388 on the cam block with a yielding stop or buffer 390 on the frame of the machine. This buffer comprises a lug projecting from the frame and a spring 392 having one end secured to the lug. The retracting movement of the cam block through the connecting mechanism depresses the rod 168 which movement of the rod brings the members for controlling the operation of the clutch, 90 through which the thread cutting and holding devices are operated, into operative 95 position.

During the normal operation of the machine the operator by varying the amount of pressure on the treadle mechanism may vary the degree of frictional contact between the clutch faces on the clutch member 288 and the high speed driving pulley 280 and thereby vary the speed of the machine. In the illustrated machine it is also possible to throw in the low speed driving mechanism without throwing the stopping devices into operation, so that the machine may be driven during its normal operation 110 by the low speed mechanism. This may be accomplished by the operator releasing the treadle rod 332 only a sufficient amount to throw in the low speed mechanism and by maintaining the treadle rod in this position. By releasing the treadle rod sufficiently to 115 throw out the high speed mechanism without throwing in the low speed mechanism, the machine may be stopped by the resistance of its parts without throwing into operation the mechanism for releasing the brake 120 125 130

on the tension wheel and the mechanism for operating the thread cutting and holding devices.

Certain features of the machine herein described are not claimed herein, but form the subject matter of divisional applications. Thus, the mechanisms of novel and improved construction and mode of operation for actuating the thread finger and looper form the subject matter of application Serial No. 412,651, filed September 25, 1920. The novel and improved channel flap closing device forms the subject matter of application Serial No. 412,652, filed September 25, 1920, and the back gage actuating mechanism forms the subject matter of application Serial No. 412,653, filed September 25, 1920.

The nature and scope of the invention having been indicated and a machine embodying the several features of the invention having been specifically described, what is claimed is:—

1. An inseam shoe sewing machine having, in combination, stitch forming devices including a curved hook needle, a channel guide, means comprising a two-part lever for moving said channel guide transversely of the direction of feed about a fixed axis, and means permitting an adjustment of the parts of said lever with relation to each other to adjust the channel guide in its path of movement transversely of the direction of feed about said axis.

2. A sewing machine having, in combination, stitch forming devices including a hook needle, a looper, a thread finger, thread holding devices for holding the thread during the first cycle of operations, and means for operating said thread holding devices while holding the thread to give up thread to the thread finger during the first cycle of operations.

3. A sewing machine having, in combination, stitch forming devices including a hook needle, a looper, a thread finger, and means acting automatically upon stopping the machine to sever and hold the thread, and to give up thread to the thread finger upon starting the machine.

4. A sewing machine having, in combination, stitch forming devices including a hook needle, a looper, a thread finger, and means acting automatically upon stopping the machine to sever and hold the thread, said thread finger being constructed and arranged to cooperate with the other stitch forming devices to form the first stitch after the machine is started.

5. A sewing machine having, in combination, stitch forming devices, driving mechanism therefor, thread severing mechanism acting during a cycle of operations of the stitch forming devices as the machine is stopped, and means for driving the stitch

forming devices at reduced speed during the action of the thread severing mechanism.

6. A sewing machine having, in combination, stitch forming devices, driving mechanism therefor, thread severing mechanism acting during a cycle of operations of the stitch forming devices as the machine is stopped, and means under the control of the operator for rendering the thread severing mechanism operative and for driving the stitch forming devices at reduced speed during the action of the thread severing mechanism.

7. A sewing machine having, in combination, stitch forming devices, high and low speed driving mechanism therefor, means under the control of the operator for shifting to the low speed driving mechanism and for stopping the machine while it is being driven by the low speed mechanism, and thread cutting mechanism acting to cut the thread while the stitch forming devices are being driven by the low speed mechanism.

8. A sewing machine having, in combination, stitch forming devices, high and low speed driving mechanism therefor, means under the control of the operator for shifting to the low speed driving mechanism and for stopping the machine while it is being driven by the low speed mechanism, thread cutting mechanism, and means acting automatically to render the thread cutting mechanism operative at a predetermined point in the cycle of operations of the stitch forming devices to cut the thread while the machine is being driven by the low speed mechanism.

9. A sewing machine having, in combination, stitch forming devices, high and low speed driving mechanism therefor, thread cutting mechanism, means under the control of the operator to throw the low speed driving mechanism into operation, means acting automatically thereafter to render the thread cutting mechanism active, and means for insuring at least a predetermined amount of low speed drive before the thread cutting mechanism is rendered active.

10. A sewing machine having, in combination, stitch forming devices, high and low speed driving mechanism therefor, thread cutting mechanism, a treadle and suitable connections acting to throw the low speed driving mechanism into operation directly on a release of the treadle, and means for insuring at least a predetermined amount of low speed drive and for thereafter rendering the thread cutting mechanism active.

11. A sewing machine having, in combination, stitch forming devices, high and low speed driving mechanism therefor, thread cutting mechanism, a controlling

- cam acting to render the thread cutting mechanism operative, means under the control of the operator to throw the low speed driving mechanism into operation, means 5 acting automatically thereafter to render the controlling cam active, and means for insuring at least a predetermined amount of low speed drive before the cam is rendered active.
- 10 12. A sewing machine having, in combination, stitch forming devices, high and low speed driving mechanism, therefor,
- thread cutting mechanism, a controlling cam acting to render the thread cutting mechanism operative, a treadle and suitable connections acting to throw the low speed driving mechanism into operation directly 15 on a release of the treadle, and means for insuring at least a predetermined amount of low speed drive and for thereafter 20 rendering the controlling cam active at a predetermined point in the cycle of operations.

ALFRED B. FOWLER.
